UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

AUTOMATICALLY-THREADING SHUTTLE.

Application filed December 3, 1923. Serial No. 678,138.

To all whom it may concern:

Be it known that I, EDWARD S. STIMPSON, a citizen of the United States, residing at Hopedale, in the county of Worcester and State of Massachusetts, have invented an Improvement in Automatically-Threading Shuttles, of which the following description, in connection with the accompanying drawings, is a specification, like characters on the drawings representing like parts.

This invention relates to loom shuttles and more particularly to shuttles of the automatically threading type.

Shuttles of the automatically threading type have heretofore been provided with a threading block, which on the first pick of the shuttle following replenishment effects a preliminary or partial threading of the shuttle, and on the return of the shuttle to the replenishing side of the loom effects complete threading of the shuttle. During the subsequent weaving operation, the thread carried in the shuttle is liable to loop or overthrow when the shuttle is arrested at the end of its flight and be cut or broken when the shuttle is again picked. The threading blocks as heretofore constructed have sought to retain the thread in the thread passage, and to this end various forms of overhangs, horns or overlapping parts have been provided. The shuttle of the present invention, however, differs from all of these and is based on the discovery that if the threading block be constructed to permit ready unthreading on the occurrence of an overthrow or loop or balloon of the thread as well as to cause the shuttle to be readily rethreaded as it is subsequently picked, many of the evils and obnoxious troubles encountered in this type of loom shuttles will be avoided.

The shuttle of the present invention, therefore, is so constructed and arranged that should an overthrow or loop occur in the thread at the end of its flight, such loop or overthrow will cause the shuttle to become partially or wholly unthreaded and be subsequently threaded on the following picks.

The overthrow or looping or ballooning of the thread is caused by the sudden arrest of the shuttle, while the thread itself as it is drawn from the filling carrier or bobbin in the shuttle continues to unwind and swirl or rotate from the end of the filling carrier

or bobbin. Since the shuttle of the present invention utilizes the swirling or rotative and longitudinal movement of the thread from the bobbin or filling carrier to unthread or partially unthread the shuttle, it is an object of the present invention to so construct the threading end portion of the shuttle that little or no interference will be presented to the looping or overthrow or swirling action of the thread as the shuttle comes to rest.

In accordance with the present invention, the threading block and threading block receiving chamber which communicates with the bobbin chamber of the shuttle are so formed and constructed that no obstruction to the free swirling and ballooning action of the thread will be presented.

An important feature of the present invention, therefore, consists in forming a threading block receiving chamber in the wood of the shuttle with side walls that diverge in non-parallel planes towards the bobbin chamber and also diverge upwardly, whereby the communicating opening between the threading block receiving chamber and the bobbin chamber is enlarged transversely and upwardly from the bottom of the threading block receiving chamber to permit the free swirl of the thread and the formation of a loop or overthrow as the shuttle comes to rest.

In the drawings:

Fig. 1 is a plan view of the threading end of a shuttle embodying the present invention;

Fig. 2 is a section on line 2—2 of Fig. 1;

Fig. 3 is a cross-section on line 3—3 of Fig. 1;

Fig. 4 is a top plan view of the threading end of the shuttle with the threading block removed, showing more particularly the threading block receiving chamber and side delivery eye communicating therewith at the narrow part of the chamber; and

Fig. 5 is an underside view of the threading block discharged.

The shuttle 1 is usually formed of wood and has a bobbin chamber 2 in which is supported a bobbin or filling carrier 3, and as usual in this class of shuttles the bobbin chamber is open at its bottom for the passage of the filling carrier or bobbin 3 when replenishment of filling is effected.

Forward of the bobbin chamber 2 the

wood of the shuttle is cut away to form a threading block receiving chamber 4 of novel construction. The side walls 5 and 6 of the threading block receiving chamber are cut 5 in non-parallel planes extending longitudinally of the shuttle and the distance between the walls 5 and 6 of the threading block receiving chamber at a point adjacent the bobbin chamber is greater than the distance 10 between the side walls 5 and 6 at points nearer the end of the shuttle, the effect being that the communicating opening between the threading block receiving chamber and the bobbin chamber of the shuttle 15 is at a greater than the distance between the side walls of the threading block receiving chamber at any point forward of the shuttle, as at b. This flaring relation of the side walls 5 and 6 towards the bobbin chamber 20 gives increased space for the swirling action of the thread as it is delivered from the bobbin, so that on the formation of a loop or overthrow there is no interference with the loop formation or overthrow of the 25 thread, as indicated by dotted lines, Figs. 1 and 2. Thus when the shuttle comes to rest and the overthrow or ballooning action of the thread is to be utilized to unthread or partially unthread the shuttle, there is no 30 obstruction presented to the free formation of the overthrow or loop.

In accordance with the present invention, the looping or ballooning of the thread as the shuttle comes to rest is utilized in throwing 35 the thread upwardly out of the thread passage, and in order that such throwing of the thread may readily occur without obstruction, the side walls 5 and 6 of the shuttle diverge upwardly from the bottom 7 of 40 the thread passage, as indicated in Fig. 3, and present a wide open unobstructed top in the threading block receiving chamber for the free exit of the looping or ballooning thread.

45 The threading block receiving chamber is provided with a thread casting device, as shown in the present illustration of the invention, and such device consists of a part connected to the threading block, which on 50 the occurrence of an overthrow of the thread, casts the thread out from the thread passage and partially or wholly unthreads the shuttle. Where a threading block is employed in connection with a shuttle as in the 55 present instance, such block has its side walls 8 and 9 diverging towards the bobbin chamber in substantial accordance with the divergence of the side walls of the threading block receiving chamber, and similarly the 60 side walls 8 and 9 of the threading block diverge upwardly from the bottom 10 of the block, in accordance with the flare or inclination of the walls of the threading block receiving chamber.

65 The threading block 11, in the present in-

stance, has a thread passage 12 extending longitudinally of the shuttle, and may be preferably provided with a bridge 13 at the front end portion of the thread passage, over which the thread passes to the side delivery 70 eye 14.

Within the thread passage of the threading block, as shown, is the thread casting and guiding device 15, the wall or edge 16 of which adjacent to the bobbin chamber 75 extends upwardly, forwardly, and laterally of the thread passage. The construction is such that should the thread as it swirls about the end of the bobbin overthrow or loop as the shuttle comes to rest, the part leading 80 through the thread casting and guiding device 15 will ride upwardly, laterally, and forwardly of the thread casting edge 16 and cast the loop to be thrown upwardly out of the thread passage.

85 The threading block as shown has a thread director 17 which extends forwardly or towards the end of the shuttle above the side delivery eye 14, and the end portion 18 of the thread director extends laterally to engage the thread on the first pick after replenishment and direct it through the opening 19 on a subsequent pick into the side delivery eye 14.

90 The side delivery eye 14 is cut through the 95 wood of the shuttle and communicates with the narrow portion of the threading block receiving chamber, as indicated in Fig. 4.

95 The frontwardly and downwardly converging side walls 5 and 6 of the threading block receiving chamber not only afford a wide communicating opening with the bobbin chamber, especially at the top of the threading block receiving chamber so as not to interfere with the swirling action of the 100 thread as it leaves the filling carrier in the shuttle, but also affords guiding means for directing the threading block into its accurate proper position in the shuttle where it 105 may be secured as usual by the cross-bolt 20. 110

115 This feature of properly positioning the threading block in the threading block receiving chamber formed as described, is of importance in an automatically threading shuttle which casts the thread or unthreads the shuttle, because the life of the wooden shuttle itself is usually not as long as the life of the metal threading block and when the wooden portion of the shuttle becomes worn or broken, the metal threading block from the old and discarded shuttle may be removed and placed in another wooden shuttle provided with the novel formation of the threading block receiving chamber wherein the side walls are formed in non-parallel 120 planes which diverge longitudinally towards the bobbin chamber and diverge upwardly 125 from the bottom of the chamber.

What is claimed is:

1. A loom shuttle having the wood of the 130

shuttle cut way at one end to form a threading block receiving chamber, the two side walls of which are cut in non-parallel longitudinally extending planes diverging upwardly from the bottom portion of the chamber and diverging longitudinally of the shuttle towards the bobbin chamber to provide a wide communicating opening in the bobbin chamber and permit swirling action of the thread as it leaves the filling carrier in the bobbin chamber, and a side delivery eye extending transversely of the shuttle and communicating with the threading block receiving chamber at the narrow portion thereof.

2. A loom shuttle of the class described provided with a bobbin chamber open at top and bottom and having the wood of the shuttle cut away in front of the bobbin chamber to form a threading block receiving chamber, each of the side walls of which is cut in a plane inclined from the bottom of the chamber upwardly and outwardly from a vertical plane passed through the longitudinal axis of the shuttle to provide a chamber having a top opening wider than the bottom of the chamber, and inclined outwardly in a direction longitudinally of the shuttle towards the bobbin chamber to provide a wide communication with the bobbin chamber permitting the swirl of the thread as it unwinds from the carrier in the bobbin chamber.

3. A loom shuttle provided with a bobbin chamber open at top and bottom and having a threading block receiving chamber, the side walls of which are cut in planes diverging upwardly from the bottom of the threading block receiving chamber and converging from the bobbin chamber towards the end of the shuttle to receive and accurately position a threading block having similarly inclined walls, and a side delivery eye extending transversely of the shuttle through the

adjacent inclined wall of the threading block receiving chamber.

4. An automatically threading loom shuttle having a bobbin chamber and a threading block receiving chamber the longitudinally extending walls of which diverge towards the bobbin chamber to receive between them a threading block having similarly diverging walls for positioning the block in said chamber and bringing the bolt holes of the block and chamber into register as the parts are assembled.

5. A loom shuttle having the wood of the shuttle cut away at one end to form a threading block receiving chamber, the two side walls of which are cut in non-parallel longitudinally extending planes diverging upwardly from the bottom portion of the chamber and diverging longitudinally of the shuttle towards the bobbin chamber, and a side delivery eye extending transversely of the shuttle and communicating with the threading block receiving chamber at the narrow portion thereof, and a thread casting device in the widened portion of the block chamber for casting the thread and partially unthreading the shuttle on the occurrence of a loop or overthrow.

6. An automatically threading loom shuttle having a bobbin chamber, a threading block receiving chamber having upwardly diverging side walls, a threading block having a thread passage flaring upwardly, and a thread casting device located in the upwardly flaring thread passage constructed and arranged to cast the thread upwardly from the flaring thread passage to partially or wholly unthread the shuttle on the occurrence of a loop or overthrow as the shuttle is arrested at the end of its flight.

In testimony whereof, I have signed my name to this specification.

EDWARD S. STIMPSON.
